(**) Term: **14 Years**

(57)

CLAIM

(21) Appl. No.: **29/161,461**

The ornamental design for a hand-held optical indicia scanner, as shown and described.

(22) Filed: **May 31, 2002**

DESCRIPTION

(51) **LOC (7) Cl. 14-02**

FIG. 1 is a left side/top/front perspective view of a hand-held

(52) **U.S. Cl. D14/428; D14/420**

optical indicia scanner of my new design;

(58) **Field of Search** D14/420, 426-431;
235/375, 378, 385, 454, 462.15, 472.02;
486; 382/312-315, 318, 319, 321; 250/203.1;
D26/37, 45, 50

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The material shown in broken lines on the lower right of
FIG. 1 comprises no part of the claimed invention.
